[57] ABSTRACT

A machine for automatically forming a bag and filling same with a dosage of granular material comprises a rotatable conveying head having a plurality of arms extending radially outwardly therefrom and each arm contains at its distal end a gripper mechanism. A transmission system rotationally drives the conveying head in an intermittent, stepwise manner to sequentially advance the gripper mechanisms to a series of work stations. The work stations sequentially and repeatedly effect formation of a paper bag from a paper strip, filling of the bag with a dosage of granular material, mechanical closing of the filled bag, attachment of a string and label to the closed bag, and covering of the labelled bag with a protective covering.

MACHINE FOR AUTOMATICALLY FORMING A BAG AND FILLING SAME WITH A DOSAGE OR GRANULAR MATERIAL

This application is a continuation-in-part application of Ser. No. 6,534 filed Jan. 28, 1970, now abandoned, which is a continuation-in-part of application Ser. No. 578,596 filed Sept. 12, 1966, which is now abandoned.

The present invention relates to a machine for automatically forming a bag-like container or receptacle from a strip of tape, introducing a predetermined quantity of a product thereinto, applying to the bag a labelled thread and covering the thus formed composite with a protective sheath or envelope.

A primary object of the present invention is to form a continuous tape or strip of filter paper into a bag which is held together by overlapping its peripheral edges. The peripheral edges are formed by folding and recessing the strip material, thereby eliminating the conventional steps of applying adhesives and/or heat-welding. By eliminating the use of adhesives and the like to hold the bag together, the quality of the beverage produced by immersion of the bag in a liquid, such as a tea bag, is increased.

Another object of the present invention is to provide means for adjusting the actual quantity of material which is introduced into the bag while the machine is in operation.

A still further object of the present invention is to provide a single machine which both forms the bags and introduces the "doses" directly into bags, thus greatly reducing the chance of contact between the product and the external environment and, more particularly, reduces the chance of contact in the zone where the product is transferred to the bag, thereby providing optimum hygiene conditions.

Yet another object of the present invention is to provide a mechanism for applying a label to the bag wherein, the label is connected to a thread thus permitting the ready extension of the thread when the label is gripped and the bag is pulled out of its protective sheath.

Still another object of the present invention is to provide means for supporting the bag during its formation without having any parts of the bag hanging.

Yet still another object of the present invention is to provide a machine for forming bags which greatly reduces filter-paper consumption although providing a bag which can rapidly extend due to infusion and swelling of the contents contained inside the bag.

Another object of the present invention is to provide a machine having the above enumerated characteristics yet whose parts are all readily accessible for inspection and repair.

An additional object of the present invention is for the bag to be formed from a lesser quantity of filter-paper.

Other features and advantages of the present invention will become evident from the following description of a preferred embodiment of the machine according to the present invention when taken in conjunction with the accompanying drawings wherein:

FIG. 1 is an almost front perspective view of a machine embodying the present invention;

FIG. 2 is a rear view of the machine with exclusive reference to the main moving parts in the machine itself;

FIG. 3 is an enlarged scale of a detail of the main moving parts shown in FIG. 2 and, in particular, of the Geneva mechanism which drives the conveying head on the machine;

FIG. 4 is a perspective view of a detail of the machine or, to be more precise, of the bag forming group;

FIG. 5 is a perspective view of the folding box inside which the bag is formed;

FIG. 6 is a plan view with cutaway of the folding box shown in FIG. 5;

FIG. 7 is a lateral view of the folding box shown in FIGS. 5 and 6, as seen in the direction shown by an arrow F in FIG. 6;

FIGS. 8, 9, 10, 11, 12 and 13 show, with exclusive reference to the sheet of filter-paper used, the various bag forming stages;

FIG. 14 represents the filter-paper infeed group for the bag forming folding box, with exclusive reference to the relevant mechanical moving parts, in a lateral view with respect to the machine, with a cutaway, in the direction of the arrow E on FIGS. 1 and 4;

FIG. 15 shows the gears which transmit the movement to the filter-paper web drive rollers and to the knife for cutting the said web on the infeed group shown in FIG. 14, in a lateral view in the direction of the arrow D on FIG. 14 and to an enlarged scale with respect to the figure itself;

FIG. 16 is, with respect to the machine, a front view with a cutaway of the bag forming group, with exclusive reference to the mechanisms which cause the movement of the sword member with which the sheet of filter-paper is pushed, as it exits from the infeed group, into the folding box wherein the bag is formed, as well as the mechanisms which provide the motion for a drive roller acting in conjunction with the reel from which the paper-filter web is unwound;

FIG. 17 is a lateral view with respect to the machine, in the direction of the arrow E shown on FIGS. 1 and 4, of the mechanisms which provide the motion for a folder group which works in conjunction with the bag folding box, that is to say, the group which actually folds a sheet in the way illustrated in FIGS. 9 and 11;

FIG. 18 is a front view of the conveying head on the machine;

FIG. 19 is a cutaway view of the conveying head shown in FIG. 18 along the same I—I axis as indicated in FIG. 18;

FIG. 20 is a general diagrammatic view pertaining to a presser group for the formed packet;

FIG. 21 is a plan view with a cutaway of the group shown in FIG. 20 in which the relevant drive unit can be seen;

FIG. 22 is the doser on the machine in question, with exclusive reference to the mechanical parts with which it is provided, seen in a perspective view;

FIG. 23 is a front view of a detail of the doser shown in FIG. 22 but with a cutaway in order to allow the parts to be clearly seen;

FIG. 24 is a perspective view of the components which serve to seal a bag after it has been filled;

FIG. 25 is a detail of the said components or, to be more precise, of the dagger shaped folder and a plan view of the relevant group;

FIG. 26 is a plan view of the mechanical operating unit for the components shown in FIGS. 24 and 25, with a cutaway to allow others to be clearly seen;

FIG. 27 shows, for information purposes, four bags in the condition in which they actually are upon completion of the operations effected at the stations S4, S5, S6 and once the station S7 has been reached;

FIG. 28 shows the labelling unit on the machine, with exclusive reference to the essential part of the said unit, in an almost front perspective view with respect to the machine;

FIG. 29 is an enlarged scale view of the unit shown in FIG. 28, seen as a perspective when looking upwards at it;

FIG. 30 is, with respect to FIG. 28, a front view of the mechanical drive assembly of the labelling unit;

FIG. 31 is a plan view of the assembly shown in FIG. 30;

FIG. 32 provides a plan view and an indication of one of the initial operating positions of the labelling unit device which carries the labelled thread to the bag;

FIG. 33 illustrates, again as a plan view, the device shown in FIG. 32 but this time in a subsequent operating position;

FIG. 34 shows a bag on to which, in an initial operation on the part of the labelling unit, the labelled thread is attached;

FIG. 35 shows a bag upon completion of the operations performed by the labelling unit;

FIG. 36 shows a multiple stapler which is pivotable on the frame of the machine and is suitable for inserting metal staples to fix a thread to a label and to a bag although in the figure it is not shown in its operating position;

FIG. 37 provides a plan view and cutaway, with exclusive reference to the relevant operating mechanisms, of the multiple stapler;

FIGS. 38, 39 and 40 illustrate, with reference to a body of the stapler, the formation stages of the staple to be inserted;

FIG. 41 is, with respect to the machine itself, a front perspective view of the bag sheathing group;

FIG. 42 is a partly front view of the group shown in FIG. 41 but with a cutaway in order that other parts can be seen more clearly;

FIG. 43 is, with respect to FIG. 42, a front view from C, again with a cutaway;

FIG. 44 shows how a folder device works on the top flap of a bag covering envelope;

FIG. 45 is an almost front perspective view of a group whose task is to take charge of the bag upon completion of the packing cycle and the group is shown at the station S10.

The apparatus according to the present invention comprises a framework structure 1 having a vertically extending portion, as best seen in FIG. 1. All the operative components are disposed on the front of the vertically extending portion of the apparatus.

Referring to FIG. 1, a conveying head 2 is centrally positioned on the vertically extending portion of the machine. The conveying head 2 is mounted on a drive shaft 4 (FIGS. 2 and 19) to rotate in a stepwise manner in 30° increments. The conveying head has a number of radially extending arms 30, 12 in this particular example, so that 12 separate stations S1, S2 . . . S12 (FIG. 18) are served during each revolution of the conveying head 2. The stepwise motion is produced by a

transmission system which is shown in FIGS. 2, 3 and 19 and which comprises a shaft 4 which carries thereon the conveying head 2. The transmission system includes a gear wheel 5 rigidly connected to the shaft 4, a gear wheel 6 (shown on FIG. 3 in phantom lines) in meshing engagement with the gear wheel 5 and which is one-third of the diameter thereof and a Geneva mechanism 7 rigidly connected to the gear wheel 6 and which is mounted for rotation on a central support 8. A spider 9 is positioned to cyclically engage with the Geneva mechanism 7 and is rigidly connected to a shaft 10. The shaft 10 is coupled with a pulley 11 and the pulley 11 is rotationally driven by a V-belt 12 from another pulley 13 rigidly connected to and rotationally driven by a larger pulley 14. The pulley 14 has a relatively large mass and serves as a flywheel and is rotationally driven by a belt 15, an adjustable pulley 17 and an electric motor 16.

During each revolution of the shaft 10 in a counter clockwise direction, the spider 9 engages, in a known manner, in one of the spaces in the Geneva mechanism 7 thereby rotating it 90° in a clockwise direction (FIGS. 2 and 3). Since there is a 1:3 step-down from the gear wheel 6 to the gear wheel 5, the latter rotates through an angle of 30°, for each 90° movement of the Geneva mechanism 7. The shaft 4, which rotates counter-clockwise as seen in FIGS. 2 and 3, rotates in a clockwise direction.

As seen in FIGS. 18 and 19, a cam 18 is provided to control the opening of a number of grippers 19 connected to the arms 30. The cam 18 is mounted upon a shaft 20 for reciprocal movement, as best seen in FIGS. 2, 3 and 19. The shaft 20 is positioned interiorly of the head drive shaft 4 and has an arm 21 rigidly connected thereto. A lever 23 engages with the arm 21 through a sliding pivot joint 22 and the lever 23 is pivotally mounted upon a support member 24. The other end of the lever 23 has a roller 25 rotatably mounted thereupon and the roller 25 is dimensioned to slide within a grooved cam 26 rigidly connected to the shaft 10. Consequently, for each revolution of the shaft 10, the cam groove 26 effectively raises and lowers the lever 23 and this oscillating motion is transmitted to the cam 18 by means of the sliding pivot joint 22. The movement of the cam 18 cams a rod 31 outwardly and the movement of the rod 31 effects a corresponding pivotal movement of an arm 32 of the gripper 19 about a pivot point 32a. The arm 32 is biased into its return position by a spring 33.

With reference to FIG. 1 and to FIGS. 4 to 17, a description will now be given of the entire bag forming group 411 and of the bag itself, the said bag forming group being by station S1.

A web of filter-paper 99 is seen being taken from a reel 72 and passing over a roller 100 supported by a leaf spring 101 integral through a rod 102 with a shaft of which mention will be made in the ensuing text. The web 99 then passes (FIGS. 4, 14, 15 and 16) inside a filter-paper infeed unit comprising a body 73 provided with a hollow shaft 74 which slides along a fixed rod 80 integral with the framework structure of the machine. The upper extremity of the said hollow shaft 74 has an annular groove 79 into which engage a pair of pins 81 connected to the prongs of a fork 113 forming the termination of an angular lever 75. The said angular lever 75 is pivoted at 76 to the framework structure of the

machine and through a roller 77 it engages with a cam 78 keyed by itself on to a shaft 41.

Consequently, while the said shaft 41 rotates, the body 73 is made to reciprocate in a vertical direction. The shaft 41 is rotationally driven through a cog wheel 42 keyed to the shaft itself and through a chain 124 which, as can be seen from FIG. 2, is mechanically connected to the motor 16. Inside the body 73 (FIGS. 4, 14 and 15) are to be found, a first drive roller 82, a counter roller 83 which rests against the former and a rotating knife 84 which is mounted, by itself, on a driven shaft 85 and works in conjunction with a fixed blade 104. This is in fact brought about by a mechanical joint (FIG. 14), comprising a worm 86 integral with a shaft 85 and a gear wheel 87 rotatably mounted on a shaft 88. This latter shaft is integral with a bevel gear 89 in meshing engagement with another identical gear 90 rigidly mounted on the aforementioned shaft 41. The gear wheel 87 is provided with a collar 91 in meshing engagement with a rod 92 protruding from the body 73. The gear wheel-collar assembly (FIG. 14) is able to slide at will axially along the shaft 88 due to the presence of a keyway 93. As a consequence of this, the rotation of the shaft 85 is produced with uniform motion by the shaft 41 despite the body 73 being allowed to reciprocate vertically.

On the front of the body 73, a knob 94 connects with the shaft 85 and is mounted on it in such a way as to be axially free yet to rotatably be in meshing engagement and the said knob 94. The knob 94 carries a gear 95 which, through another idler gear 96 (see FIG. 15), operates another gear mounted on a shaft 98 to which the driving roller 82 is rigidly coupled. These gears are intended to be used to substitute one another in such a way that it be possible to vary the relevant speed of the drive roller for the rotating knife. When the knob 94 is slid axially, the paper drive mechanism can be disengaged. A cog wheel 83a rigidly mounted on a shaft 83b supporting the roller 83 takes its drive from a cog wheel 97 whose number of teeth is identical.

From the description given in the foregoing text concerning the operation of the filter-paper infeed group, the following can be seen: the web of filter-paper 99 passes over the roller 83 kept in contact with the drive roller 82, then in front of the rotating knife 84 and the fixed counter blade 104. Below the body 73, rod shaped means 103 are provided with which to keep a hold on and slightly arch the sheet of paper which will be cut by the knife 84 and by the fixed counter blade 104.

On account of the mechanical connections described, the web of paper is continuously moved by the drive roller 82 while the body 73 performs its vertical travel over a rectilinear trajectory.

The previously mentioned collar 100, spring loaded at point 101, prevents small tears from being made in the web while the body 73 is reciprocating and thus the stress to which the web is subjected remains practically constant. The overall speed of the web, when the body 73 is travelling downwards, will be given by the sum of two relevant velocities directed in the same downward direction, that is to say, the velocity of the body itself and that due to the motion of the web.

At the moment when the return speed in an upward direction of the body 73 corresponds to that of the downward infeed speed of the web, that is to say, when the two relevant velocities are, with respect to a fixed

point, the same, despite the velocities being in opposite directions, the rotating knife operates and cuts a sheet off the end of the web of filter-paper while the paper is being held between two rod shaped members 103 and is practically immobile in the air.

In order to keep the web infeed uniform and, consequently, to keep constant the tractive force on the web, the reel 72 is driven externally by a roller 105 (FIGS. 1, 14 and 16) carried by an internally hollow arm 106 which is able to rotate inside the shaft 41 by which it is supported.

The said roller 105 is rigidly mounted on a shaft 108 which passes inside the arm 106 and is integral with a pinion 109 in meshing engagement with a chain 110 connected to another pinion 111. The latter is rigidly mounted on the said shaft 41 which supports the arm 106 and, as stated above, rotates inside it.

With reference to FIGS. 4, 5, 6, 7, 16 and 17, a description will now be given of the group which forms the bag from a sheet of paper by folding it in accordance with the sequence of operations illustrated in FIGS. 8 to 13.

A sword member 28 carried by a sleeve 114 slides on the previously mentioned shaft 115 which extends towards the outside.

Laterally the said sleeve 114 (FIGS. 4, 16 and 17) has a pin 116 which engages with a fork type link block 117 carried by an operating arm 118, hinged at 119 on to the framework structure of the machine and in mesh engagement with a cam 121 through a roller 120, the former being carried by a shaft 122. The said shaft 122 is integral with a pinion 123 (FIG. 2) driven at the rear of the machine by the chain 124 which operates the previously described pinion 42 mounted on the shaft 41.

Belonging to the same bag forming group, there is a fixed folding box 125 (FIGS. 1, 4, 5, 6, 7 and 16) and the head of the sword member 28 is designed to fit into the folding box carrying with it the sheet of paper taken in the initial section of its travel, which due to the pressure exerted against it by two fixed shoulders 103a and 103b with which the folding box 125 is provided, is folded into a U around the head of the sword member (as illustrated in FIG. 8). Crosswise to the folding box 125 a pair of folders 126 and 127 are located at the sides of the sword member towards the framework structure of the machine and the folders operate in a direction which is transverse to that of the sword member infeed.

The cam 121 is shaped so as to essentially halt for a short time the infeed movement of the sword member 28 when the bag being formed is in front of the said transverse folders 126 and 127 which, as has been said, are intended to form the first lateral folds on the bag being formed (as illustrated in FIG. 9). The folders 126 and 127 are connected to a bracket 500 mounted on a shaft 501 supported by a sleeve 802 integral with the framework structure of the machine. The said shaft 501 is provided (FIG. 17) with a pin 503 which engages with a fork type link block 504 carried by an operating arm 505, hinged at 506 on to the framework structure of the machine and in mesh engagement, through a roller 507, with a cam 508 carried by the shaft 122. In this way it is possible for the folders 126 and 127 to be displaced transversely with respect to the direction in which the sword member 28 moves.

Furthermore, the bracket 500 carries a pin 509 to which two arms 510 and 511 are hinged and each of these (see FIGS. 5, 6 and 7) supports a rod 512 to which a shaped plate 513 is rigidly coupled.

The folding box 125 has fixed to it, at the top and at the bottom, respectively, a strip 514 and a strip 515, both of which are bent into an L with the vertical wing following the shape of the plate 513.

Each of the arms 510 and 511 is connected to a roller 530 which slides in a contoured guide 531 machined into a plate 532 integral with the folding box 125. Each guide 531 has a rectilinear section and a section converging towards the axis of the pin 509.

In this way when each roller 530 is in the inner position next to the folding box 125, the plates 513 are in the position shown in phantom lines in FIG. 7, while when the rollers 530 slide in the converging sections of the guides 531, the plates 513 are carried to the position shown in continuous lines on FIGS. 5 and 7, that is to say, they are almost next to the strips 514 and 515.

On the upper and lower edge of the inner wall 517 of the folding box 125, at the point where the strips 514 and 515 commence, there are two helical folders 518 and 519.

A second pair of helical folders 520 and 521 is milled into the folding box 125 further on after the folders 518 and 519 (see FIGS. 5 and 7).

Two pairs of hollowing or recessing elements 522, 523, 524 and 525 (see FIGS. 5, 6 and 7) follow on after the aforementioned folders 520 and 521.

A third pair of helical folders 526 and 527 (see FIG. 5) are milled into the folding box 125 after the aforementioned second pair of helical folders 520 and 521.

A diaphragm 528 supported by the folding box 125 extends axially inside the folding box and more will be said about this diaphragm in due course.

A fourth pair of helical folders 529, only one of which is visible in FIG. 6, are milled into the folding box 125 at points corresponding to the lateral lower and upper extremities of the folding box and these extend in the opposite direction to the pair of helical folders 518 and 519.

With reference to the foregoing, a description will now be given of how a bag is formed, starting from the sheet already handled by the folders 126 and 127.

Subsequent to the halt enforced by the cam 121, the sword member 28 starts again to enter inside the folding box 125. Initially, the sheet comes into contact with the first pair of helical folders 518 and 519 and then with the second pair of helical folders 520 and 521. The flaps of the sheet are straightened in this way and their front part turned over so that it takes on the condition shown in FIG. 10. At this point, due to the operation of the cam 508, the shaft 501 moves in the direction of the arrow 500a (FIG. 17). Thus the plates 513 enter into contact with the flaps of the sheet which have just previously been straightened by the pair of folders 518 and 519 and the plates 513 turn the flaps over in part on to the strips 514 and 515, moving on to the position shown in FIGS. 5 and 7. Upon completion of this operation, the sheet is in the state shown in FIG. 11.

The sword member 28 continues to enter inside the folding box 125 and thus the sheet passes to the third pair of helical folders 526 and 527 and subsequently to the hollowing or recessing elements 522, 523, 524 and

525 and finally to the fourth pair of helical folders 529.

The third pair of helical folders 526 and 527 causes the remaining part of the straightened flaps of the bag to be turned over on to parallel planes perpendicular with the vertical extension of the bag while the hollowing or recessing elements 522, 523, 524 and 525 cause the bilateral seams of the bag to be formed into a wedge over the lateral surface of the sword member 28.

10 In this way the bilateral folds on the bag being formed are fashioned and the condition of the bag, prior to it being moved along to the fourth pair of folders 529 by the sword member 28, can be seen in FIG. 12.

With further penetration of the sword member 28 into the folding box 125, the flaps of the bag, which as has already been said are on parallel planes perpendicular with the vertical extension of the bag being formed, come into contact with the fourth pair of helical folders 529 which, in conjunction and in contrast with the diaphragm 528, turn the flaps over again and position them on one side of the bag.

When the various folding operations have been completed, the formed bag which leaves the folding box 125 is in the condition illustrated in FIG. 13.

25 FIGS. 20 and 21 show a curved member 43 mounted on the end of a rod 35 which is supported by an arm 36 made integral with the framework structure 1 of the machine. The said rod 35 is able to slide inside the arm 36. The curved member 43 has fixed to it: a first support member 34, two pressers 44 and 45 and a second support member 46, all of which are disposed in such a way as to be called upon to operate at stages corresponding to the stations S1, S2, S3 and S4, that is to say, the support member 34 corresponds to the station S1, the pressers 44 and 45 correspond to the station S2 and to the station S3, respectively, while the support member 46 corresponds to the station S4.

30 The rod 35 engages, through a link block 37a, with a lever 31 which oscillates around a spindle 38 and via a roller 39 is in mesh engagement with a cam 40 fixedly mounted on the aforementioned shaft 41.

35 A flexible strip 131 is fixed to the curved member 43 (see FIG. 21) at a point corresponding to the support member 34. The said strip 131 has its extremity 132 pointing towards the support member 34 in such a way as to be able to function inside it and it is provided with a feeler 131a which is operated by a roller 133a mounted on an arm 133 fixed to the support arm 2a of the conveying head 2.

40 The flexible strip also has an axial groove 131b (FIG. 20), the purposes of which will be defined in the ensuing text.

45 A description will now be given of how the formed bag is taken from the folding box 125 to the conveying head 2 at a point where the station S1 is located and thence from this station to the station S4.

50 With the conveying head at a standstill, one of the arms 30 or to be more precise, the one considered as being 30' (see FIG. 21) is located at a point corresponding to the station S1 with the relevant gripper 19 open.

55 The shaft 41 rotates and the cam 40 causes the lever 37 to rotate clockwise with the effect that the rod 35 slides inside the arm 36 and this brings about the approach of the support member 34, the pressers 44 and 45 and of the support member 46 towards the arms 30 of the conveying head 2.

60 The shaft 41 rotates and the cam 40 causes the lever 37 to rotate clockwise with the effect that the rod 35 slides inside the arm 36 and this brings about the approach of the support member 34, the pressers 44 and 45 and of the support member 46 towards the arms 30 of the conveying head 2.

While this approach is taking place, the feeler 131a of the strip 131 is tripped by the roller 133a and this compels the extremity 132 of the said strip to penetrate inside the support member 34. The gripper 19 is thus located inside the slot 131b of the strip 131 but this does not in any way impede the movement of the said strip.

When the formed bag exits from the folding box 125, propelled by the sword member 28, it is momentarily supported by the support member 34. The sword member 28 continues to push the bag until its base is buffered against the folded tip 132 of the strip 131.

Due to the special way in which the head of the sword member is shaped, the result is that the extremity 132 is bent inside the head in such a way as to cause a folding line to be made on the bottom of the bag.

This is still with the conveying head 2 at a standstill.

At this point the gripper 19 which works in conjunction with the arm 30' closes, the cam 40 causes the displacement of the support member 34, the pressers 44 and 45 and the support member 46 from the arms of the conveying head 2 and the sword member 28 returns to its commencing position.

The conveying head 2 completes a first rotation of 30° thus carrying the bag from the station S1 to the station S2.

While in accordance with the foregoing description a new bag is being taken to the conveying head 2 at the station S1, the presser 44 moves, at the station S2, towards the terminal part of the arm 30' so as to emphasize the formation folds in the bag. An identical action takes place when the bag is carried to the station S3 but this time it is effected by the presser 45.

With the considered arm 30' at the station S3, the conveying head 2 performs another 30° rotation and this carries the considered bag to the station S4 at a point where the doser unit operates 137 (FIG. 1). An explanation of this unit will now be given with reference to FIGS. 1, 22 and 23.

The doser 137 is provided with a charging hopper 138, the lower part of which terminates with a cylindrical cavity 139 inside which a drum 140 is housed and this, through a shaft 142 which is suitably supported by the structure carrying the doser, is connected to a Geneva mechanism 141 operated by a centering device 143. The said drum 140 has a number of through holes 150 drilled in it and these are suitable for channelling the product stored inside the hopper 138.

The centering device 143 is keyed on to a driven shaft 144 and it is able to run axially to it.

The shaft 144, in turn, takes its motion from a drive shaft 145 to which it is coupled by means of a right angled worm gear 144a.

A pinion 172 rigidly mounted on the shaft 145 engages with a chain 124 mechanically connected to the motor 16 (see FIGS. 2 and 22) and drives the shaft 145. It can be seen, therefore, that when told to do so by the centering device 143, the drum 140 rotates intermittently inside the cavity 139.

The shaft 142 is housed inside another shaft 146 and the lower part of the latter is integral with a leveller 147 which is flat up against the upper face of the drum 140. The leveller 147 has a slot 148 inside which a rod 149 is permanently inserted and the lower end of the said rod is normally almost flat up against the upper face of the drum 140.

The shaft 146 performs a reciprocating rotatory motion derived from a cam 167 rigidly mounted on the shaft 144. The transmission occurs through a lever 168, one extremity of which is coupled to a link block 169 and the other pivoted 170 to the structure carrying the doser. The engagement of the said lever 168 with the cam 167 is by means of a roller 171.

The rod 149 is given a linear reciprocating motion on a plane perpendicular to the upper face of the drum

10 140 and this movement is derived from a cam 166 rigidly mounted on the shaft 145. The said cam 166 is connected to the rod 149 by means of a lever 149a which engages with the said cam 166 through a roller 149b.

15 A plunger 151 seen more clearly on FIG. 23, operates in the lower region of the drum 140, the purpose of this being to remove from the hole which arrives in its vicinity, a certain quantity of the dose of the product contained in the hole, prior to levelling.

20 The said plunger 151 passes through a hole drilled in the base of the charging hopper 138 and pending the arrival of the considered hole in the drum 140 coincident with the plunger 151, the product is constrained in the holes by the base of the hopper 138.

25 In its normal position, the upper extremity of the plunger 151 almost brushes against the lower face of the drum 140.

30 The plunger 151 is given a reciprocating movement on a plane perpendicular to the lower face of the drum

35 140 and this motion is derived from a cam 165, rigidly mounted on a shaft 145. The plunger 151 works in conjunction with the cam 165 through a rod 155 connected, by means of a pin 156, to a link block 157 forming part of a lever 158 which is pivoted at 158a to the structure carrying the doser. The said lever 158 works in conjunction with another twin arm lever 159 keyed on to a shaft 159a supported by the structure carrying the doser and the connection is brought about by a pin 160 engaging in the slots 160a and 160b in the lever 158 and in one arm of the lever 159, respectively.

40 The other arm of the lever 159 engages, through a roller which cannot be seen in the drawing, with the cam 165.

45 A firm connection between the two levers 158 and 159 is provided by a rod 161 sliding axially inside a guide box 161a supported by the structure carrying the doser.

50 The sliding movement of the rod 161 is realized by means of a screw 162 and control wheel 163 connected to the aforementioned rod.

55 In this way it is possible to vary the leverage and, in consequence, the travel of the plunger 151 and the reasons for this will be explained further on.

55 The regulating system is designed in such a way that the lower limit of the plunger 151 is always on a level with the lower plane of the doser whilst the upward stroke can be varied.

60 A lever 161b makes it possible to lock the rod 161 in the established position.

65 A telescopic hollow shaft 153 (seen best in FIG. 23) is located on the base of the hopper 138 at a point corresponding to a hole 152 drilled in the said base and coaxial to the rod 149. The moving part 154 of the telescopic hollow shaft 153, suitably shaped to form a wedge, is able to penetrate inside the bag carried by the conveying head 2.

A cam 164 mounted on the shaft 145 controls the movement of the aforementioned moving part 154, this being a reciprocating motion in a direction perpendicular to the mouth of the bag carried by the conveying head 2, through a lever 154a pivoted to the shaft 159a. The said lever 154a engages with the cam 164 by means of a roller 154b and is connected at point 154c to a rod 154d fitted to the said moving part 154.

A description will now be given of the doser mechanism.

With the conveying head 2 at a standstill, the gripper 19 corresponding to the arm 30' carrying the considered bag is open and the bag itself is being held by the support member 46 of which mention has already been made in the foregoing text.

The product contained in the charging hopper 138 fills the holes 150.

The drum 140 rotates intermittently in a counter clockwise direction and as a considered hole 150 approaches the leveller 147 and is positioned by the plunger 151, the drum 140 comes to a halt.

The plunger 151 moves upwards and inserts itself in the said hole 150 thereby expelling from the hole a certain quantity of the product contained in it and the said quantity represents a dose.

At this point, the leveller 147 rotates clockwise until the upper mouth of the considered hole 150 is sealed and the plunger 151 returns to its initial position very close to the face of the base of the drum 140, thus preventing the product from dropping out.

The drum 140 rotates again in a counter clockwise direction and this particular rotation is accompanied for a certain part of the way by the leveller 147 which keeps the upper mouth of the considered hole 150 sealed while the lower mouth is closed by the base of the charging hopper 138.

The counter clockwise rotation of the leveller 147 ceases once the said hole 150 is positioned almost at a point corresponding to the rod 149 while that of the drum 140 terminates when the said hole 150 is right by the said rod 149.

At this stage, the moving part 154 and the rod 149 operate in succession.

The moving part 154 travels downwards and places itself inside the bag while the rod 149 goes into the hole 150 thus forcing out the product contained in it and this product is transferred into the said bag.

Once this cycle is over, the rod 149 and the moving part 154 return to their initial position, the gripper 19 corresponding to the arm 30' under consideration, closes, thereby holding on to the bag and then the conveying head 2 subsequently rotates a further 30°, thus carrying the bag to a position corresponding to the station S5.

In order that it be possible to regulate the doser whilst the machine is running, provision is made for the centerer 143 not to have to engage with the Geneva mechanism 141 and yet still to rotate.

As already stated, the centering device 143 is able to slide axially with respect to the shaft 144. This slippage is manually controlled by a lever 173, pivoted at point 174 to the structure carrying the doser and provided with a fork link 175 which connects with a groove machined into the hub on the centerer 143.

The said lever 173 is also visible in FIG. 1.

When the lever 173 is moved in a clockwise direction, the centering device 143 is made to move upwards

so that it is put in a position where it does not work in conjunction with the Geneva mechanism 141.

In this way the drum 140 does not rotate and, if necessary, it is possible to vary, by moving the rod 161, the leverage ratio to which the plunger 151 is subjected and thus to also modify the movement of the plunger itself and thereby increase or decrease the expulsion of the product from the considered hole 150, that is to say, cause the dose of the product to be of a greater or of a lesser quantity.

A description will now be given of the component parts used to fold and overlap the flaps on the bag filled with the product, in such a way as to seal the actual mouth of the bag. The component parts in question 15 mainly operate in the neighbourhood of the aforementioned station S5 and they can be seen in FIGS. 24, 25 and 26.

FIGS. 24 and 25 show two guide members 60 and 61, respectively, which converge towards the station S5 and cause the flaps on the filled bag to be brought together while the bag is being transferred from the station S4 to the station S5.

An initial component 48, virtually in the form of a dagger is supported by a member 62 connected to a shaft 62a.

A first stationary abutment 48' is shown and more will be said about this in the ensuing text.

A second stationary abutment 49 has a notch which reproduces the shape of the dagger folder 48 and is on 30 almost the same plane as the dagger folder itself. The abutment 49 is borne by a support 49a fixed to a structure 49b and the latter is connected to the framework structure of the machine.

On FIG. 24, there is a presser 49c which operates by 35 going towards the abutment 48' in order to contribute towards bringing together the flaps on the bag carried to the station S5. The said presser 49c is supported by a member 49d which is connected to a hollow shaft 49e sliding on the shaft 62a.

Two fingers 50 and 51 are held in such a way that 40 they are able to rotate around their own axes 53 and 54 by a support member 52 which is connected to a shaft 52a sliding on the shaft 49e and inside a support arm 52c fixed to the framework structure of the machine.

Two rollers 55 and 56 connect with the rear end of the finger 50 and 51, respectively, and these are engaged with two slots 57 and 58, respectively, machined into a plate 59 carried by the structure of the machine.

With reference to FIGS. 2 and 26, a description will 50 now be given of the mechanical parts which move the dagger folder 48, the presser 49c and the fingers 50 and 51.

A cam 271 rigidly mounted on a shaft 192 supported by the structure 49b is shown and the said shaft 192 is connected to a pinion 193 which engages with a chain 194 (FIG. 2) and takes its motion, through a pinion which is not illustrated, from the shaft 145 on which the previously mentioned pinion 172 is mounted.

The said cam 271 engages with a roller 269a connected to one of the extremities of a lever 269 which is pivoted at point 270 to the structure 49b, the other extremity being connected to the rear end of the shaft 62a.

A second cam 267 is also rigidly mounted on the shaft 192 and this engages with a roller 265a connected

to one of the ends of a lever 265 which is pivoted at point 266 to the structure 49b, the other extremity being connected to the rear end of the shaft 49c.

A third cam 275 is rigidly mounted on a driven shaft 189, supported by the structure 49b and this takes its motion from the shaft 192 through two cog wheels 190 and 191 which mesh with each other and have the same number of teeth, the latter being rigidly mounted on the shafts 189 and 192, respectively.

The said cam 275 engages with a roller 277 connected to one of the ends of a rod 276, the other extremity of which is connected to one of the ends of an L-lever 272, pivoted at point 273 to the structure 49b, the other extremity of which is connected to the rear end of the shaft 52a.

With reference to the above, it can be seen from the explanation given that the shafts 62a, 49c and 52a and consequently also the dagger folder 48, the presser 49c and the fingers 50 and 51 are provided with a reciprocating movement in a direction perpendicular to the direction of the bag when it is being carried by the conveying head 2.

A description will now be given of the procedure adopted to fold and overlap the upper flaps on the bag in order to seal the mouth of the bag, with particular reference not only to FIGS. 24, 25 and 26 but also to FIG. 27 on which, purely for information purposes, four bags are shown in the condition in which they find themselves upon completion of the operations carried out at the stations S4, S5 and S6 and once the station S7 has been reached.

The filled bag has arrived at the station S5, the conveying head 2 is at a standstill and the gripper 19 corresponding to the considered arm 30' is closed.

When told to do so by the cam 267, the presser 49c presses the flaps on the bag against the abutment 48', thus bringing them closer together. The presser 49c then returns to its initial position.

At this stage, the cam 271 causes the dagger folder 48 to take transverse action on the bag and to fold its upper part which passes under the abutment 48' and is turned over on the abutment 49 where due to a reaction effect, two lateral oblique folds are formed and these make it possible to bring the lateral ends of the said upper part on to planes almost perpendicular to the abutment 49.

Now, operated by the cam 275, the fingers 50 and 51 move towards the abutment 49 and, on account of the special way in which the slots 57 and 58 are shaped, rotating around their respective fulcra 53 and 54, they approach each other above the said abutment 49 and turn the aforementioned lateral extremities of the upper part of the bag over on to the dagger folder 48 which gradually returns to its initial position.

In this way the bag is located by the station S5 and is in the condition illustrated in FIG. 27, once the operations described above have been completed.

The dagger folder 48 and the fingers 50 and 51 return to their initial position whilst the conveying head 2 undergoes a 30° rotation and transfers the considered bag from the station S5 to the station S6.

Whilst the transfer is under way, the upper part of the bag is straightened and placed on its original plane and thus when the bag arrives at the station S6, it is in the condition illustrated in FIG. 27.

In order to achieve this (see FIGS. 24, 25 and 26), a helical surface 63 is provided, machined into the sup-

port 49a and opposite a flexible strip 64 which gradually straightens the upper part of the bag as it is being transferred from the station S5 to the station S6.

At the station S6, with the conveying head 2 immobile and the gripper 19 corresponding to the considered arm 30' closed, the folds pre-formed at the station S5 are made more definite and this is done through the medium of a presser 65 (see FIGS. 24 and 26), connected to an arm 66, supported by the structure 49b.

10 The said presser 65 moves towards an abutment 67 which is also supported by the structure 49b.

The action of the presser 65 is controlled by a cam 280 which engages with a roller 282 connected to one of the extremities of an arm 281, the other extremity 15 of which is secured to one of the ends of an L-lever 278 pivoted at point 273 to the structure 49b, the other end of the said lever 278 being connected to the arm 66.

Once the presser 65 has performed its operation, the conveying head 2 undergoes a 30° rotation and transfers the considered bag to the station S7.

As is obvious from FIG. 27, the considered bag arrives at the station S7 with the point on the upper part, or head, folded over on itself and, as will be seen later on, this will have a labelled thread attached to it. The folding of the point occurs during the stage when the considered bag is being transferred from the station S6 to the station S7.

This is achieved through a pair of helical guides (see FIG. 24) provided by the members 68 and 69, the first 30 of which is longer than the other and stretches beyond the horizontal line coincident with the central axis of the station S7. The lower part of the member 68 has a contour 70 and this is used by the considered bag once it is at the station S7, to fold the point back over on itself.

Thus, up to the present, the bag has completed a semi-circle and has passed successively through seven stations.

With reference to the FIGS. 28, 29, 30, 31, 32, 33, 40 34 and 35, a description will now be given of the component parts used to join a labelled thread to the considered bag; these parts belong to a labelling unit which operates in the zone corresponding to the station S7.

With particular reference to the FIGS. 28, 29, 30 and 45 31, a disc 178 is located on a horizontal plane which crosses with the plane on which the conveying head 2 lies on the axis of the transverse center line.

The said disc 178 is supported by a shaft 179 (FIG. 30) which has mounted on it, in such a way that it is able to move axially with respect to the said shaft, a cog wheel 180, provided with a collar 195 having a groove 196 which engages with the two pins 198 connected to the extremity of a lever 197 (see FIG. 31), pivoted at point 199 to a shaft supported by the aforementioned structure 49b.

This lever, through an arm 197a to which it is connected, supported in such a way that it is able to oscillate from the structure 49b, is connected to a cam 200 fixedly mounted on the previously mentioned shaft 192.

Two toothed quadrants 181 and 182 engage with the cog wheel 180 and these are connected to two levers 181a and 182a, respectively, which are pivoted at points 183 and 184, respectively, to the structure 49b.

65 The levers 181a and 182a engage, through two rollers 185 and 186, respectively, to which they are con-

nected, with two cams 187 and 188 rigidly mounted on the aforementioned shaft 189.

The said two quadrants 181 and 182 are disposed on planes, one above the other (see FIG. 30).

In this way, the cams 200, 187 and 188 cause the cog wheel 180 to engage, first with one and then with the other, with the quadrant 182 and with the quadrant 181 and this results in the disc 178 rotating in stages of a 20° rotation and subsequent 70° rotations in a counter clockwise direction (see FIGS. 31, 32 and 33).

The disc 178 which in this particular instance is best seen in FIGS. 32 and 33, has four compartments 201, 202, 203 and 204, corresponding to which there are the same number of grippers 205, each of which, as will be seen further on, is able to hold on to the end of a thread during the predetermined work phases.

The division of the disc into four parts is in relationship to the circumferential span of each of the four parts and this has to suit the length of the thread with which a label will be attached to the considered bag carried to the station S7.

In the compartments 201, 202, 203 and 204, there is also a second pair of grippers 206 which, as will be seen in the ensuing text, are intended to hold the labels which arrive, one after the other, for the bags carried to the station S7 by the conveying head 2.

At certain times, the grippers 206 are subjected to the control of a cam 210, located below the disc (see FIGS. 29 and 30) which causes them to open.

The cam 210 is supported by a shaft 211 threaded inside the shaft 179 (see FIGS. 29, 30 and 31), at the top of which there is a lever 212 (FIG. 31) connected to a tie rod 213 which, in turn, is connected to an oscillating lever 214 connected to the lever 182a through a link rod 215.

It thus follows that the given angle of rotation of the lever 182a produces a corresponding rotation on the part of the cam 210 and the consequent operation of the grippers 206 concerned, as a result of the rotation of the control cam 210.

A pusher 216 is shown on FIGS. 28, 30 and 32 and this has a cutaway 216a along its termination and more will be said about this in due course.

The pusher 216 is secured to a support arm 216b which, in turn, is supported by a shaft 255 suitably sustained by the structure 49b.

The upper extremity of the shaft 255 (FIG. 31) is integral with a lever 255a which is fastened, by means of an arm 255b, to a cam 255c rigidly mounted on the shaft 189. A further lever 256 which engages with a seat specially machined into the lever 255a, pivoted at point 258 to the structure 49b, subjects the shaft 255 to the action of a cam 259 with which the said lever 256 engages through a roller 260.

Thus in this way, not only does the pusher 216 have a rotatory movement but is also subjected to a vertical translation for reasons which will be clarified later on.

A block 220 (see FIGS. 28, 30 and 32) is provided and this serves in conjunction with a stapler, about which more will be said in the ensuing text, which attaches a label to the thread to be affixed to the considered bag.

The said block 220 is supported by a rod 261, suitably carried by the structure 49b and able to move vertically.

The movement of the rod 261 depends, see FIGS. 30 and 31, on a cam 264 to which it is connected through a lever 262 pivoted at point 258' to the structure 49b. The actual engagement takes place through a roller 263.

A small support 218 carried by the structure of the machine receives, using conventional procedure, a label 217 from a continuous web 283 (FIGS. 28 and 1) taken from a reel 283a.

10 A description will now be given, with particular reference to the FIG. 32, of the operating stages for the labelling unit and, first of all, of how a thread is carried by the disc 178 and how a label is fastened to the said thread.

15 A thread 207 taken from a spool 209, visible in FIG. 1 passes along a guide-tension device 208 (see FIG. 28).

For the initial application of the thread, it has to be manually taken to the considered gripper 205 which, in 20 this particular instance, is 205a (FIG. 32). After this, the thread is automatically picked up by the gripper 205 and a clarification of this operation will be given later on.

With the conveying head 2 at a standstill, the considered bag is located at the station S7; the disc 178 is immobile and is in the position illustrated in FIG. 32; the block 220 is in the lowered position.

Under these conditions, the pusher operates 216 and its arm 216b, sectioned by the cam 255c, rotates in a 25 clockwise direction, that is to say, towards the disc 178.

It follows that the cutaway 216a comes into contact with the thread 207, considered in the foregoing text, as it leaves the guide-tension device 208 and that it 35 pushes the thread until it has been taken, initially, to the label 217 on the support 218.

The arm 216b continues its own rotation and thus the label 217 pushed up against a stationary abutment 219 supported by the structure carrying the labeller and against the side of the block 220, is wedged between them while the cutaway 216a travels slightly past the block 220.

Once this position has been reached, the arm 216b effects a short halt during which a first stapler, more about which will be said in the ensuing text, clips a metal staple to the label 217 and attaches the thread to the label making use of the block 220. The said arm 216b then moves out of the zone, as does also the block 220 which, operated by the cam 264, is lifted, thus freeing the thread.

From this moment on, the arm 216b resumes rotating in a clockwise direction while the cutaway 216a inserts the label complete with the attached thread, between a considered gripper 206a which has previously been 55 made to open by the cam 210.

When the label 217 is fully inserted in the gripper 206a, the cam 210 rotates and this causes the gripper to close and keep a firm hold on the label.

At this juncture, the cam 259 causes the rod 255 to 60 be pushed upwards and this results in the arm 216b being lifted and in the cutaway 216a ceasing to be in contact with the label. These items move out of the zone and return to their initial position.

When this condition occurs, the disc 178 completes a counter clockwise rotation of 20°.

It should not be overlooked that while the rear of the label continues to be, with respect to the direction in

which the disc rotates, radial to it, the front part remains curved forwards due to the tension of the thread preceding it.

When the rotation is over, the disc 178 is located in the position illustrated in FIG. 33.

The gripper 205a with which the thread is being pulled, finds itself in the position F in the region of an arm 226 which is connected to certain operating parts which, in the case at present being described, that is to say, the first application of a thread to a bag, although contributing, have no real effect and thus the relevant description will only be given when mention is made of how the subsequent thread is attached to another bag.

The disc 178 undergoes a counter clockwise rotation of 70°. Upon completion of this rotation, the gripper 205a finds itself in the position A (see FIG. 32) and a fresh label is inserted into the gripper 206b which is always in the position B when the said rotation has been completed.

The disc 178 performs a further 20° rotation.

The conveying head 2 continues to be at a standstill.

Following this rotation, the disc 178 is back in the position shown in FIG. 33.

The gripper 205a is located next to the contour 70 on which, as already stated, the point on the top of the considered bag is folded.

At this stage there is a fresh operation on the part of the aforementioned arm 226.

As is evident from FIG. 33, the previously considered label 217 is held in the gripper 206a.

Behind the said gripper there is a cutting edge 224 used in conjunction with a knife 225 carried by the arm 226 for cutting the thread 207 at the back of the label 217.

The knife 225 is hinged to the arm 226 and is pushed outwards by a spring 246.

Furthermore, the knife 225 is provided with a button 248 which fits into a shaped guide 249 and it also has a protrusion 250.

When the arm 226 commences rotating in a counter clockwise direction, the button 248 pushes the knife towards the arm. Once the button has ceased pushing, the knife, under the pressure of the spring 246 rests itself with the protrusion 250 against the aforementioned cutting edge 224, extending from the disc.

This mechanism is provided in order to match the two cutting profiles should the disc 178 be subjected to eventual rotatory play.

A strip 227 carried by the same arm 226 forces, to the rear of the label 217, the thread 207 into the gripper 205b which is in the position E while a roller 228 and a tongue shaped member 229, also carried by the arm 226 guide the taut thread as it is inserted into the said gripper 205b. This is done to ensure the end of the thread being carried to the disc 178 is automatically grasped.

An insertion member 230 fastened to the arm 226 has the task of forcing the front part of the label under a protrusion 231 presented by the disc.

The movement of the arm 226 (FIG. 31) takes place through a cam 226a, rigidly mounted on the shaft 189 which is connected to the said arm by means of a rod 226b secured to the extremity of a lever 226c integral with the support shaft 226d of the aforementioned arm 226.

While the arm 226 is operating, next to the gripper 205a an oscillating insertion member 222 (see FIGS. 28, 30 and 33) operates. This particular member is connected to a block 222a through a spacer element 5 and the inserter presses the thread at the rear of the gripper 205a (FIG. 33) against the block, frees the thread and carries it to the contour 70. The operation of the inserter member 222 continues until the thread straddles the point of the bag which is folded on the contour 70.

At this point, in the zone between the inserter member 222 and the contour 70, a second stapler, more about which will be said in due course, fits on another metal staple and secures the thread to the bag by pressure applied against the block 222a.

The inserter member 222 moves away. The bag, thread and label under consideration are in the condition illustrated in FIG. 34.

With the conveying head 2 still not moving, the gripper 19 corresponding to the considered arm 30' is open and the bag is supported by a sustaining member 411 which is visible in FIG. 28 and is secured to the presser 65, about which a description has previously been given, next to the arm 30'.

As already stated, the rear skirt of the label 217 is kept radial to the disc 178. This part of the label extends radially to the outside of the disc 178. A curved area 232 partly surrounding the disc 178 is shown on FIG. 33. This has an internal groove 233 which extends the full length of the area 232 or, to be more precise, from point 234 to point 235.

This groove is shaped in such a way that it can be swept over by the protruding skirt of the label 217.

Once the arm 226 has ceased operating, it is carried outside the zone and rotates in a clockwise direction.

The disc which is temporarily at a halt, completes a 70° rotation. Subsequently the said protruding skirt of 40 the label 217 sweeps across the considered groove 233 and picks up the thread inside a volume which is constantly reduced until the label is on top of the bag to which the end of the considered thread has previously been attached.

The thread then remains caught between the rear skirt of the label and the bag.

Now the disc is temporarily immobile and is again in the position shown on FIG. 32.

At this stage another inserter assembly 410 comes into operation as visible in FIGS. 29 and 33, and comprises a presser 236 carried by an arm 237 integral with a rotating shaft 238 supported by the structure 49b.

The said shaft 238 (see FIGS. 30 and 31) takes its motion from a cam 238a to which it is connected through a lever 238b with which it is integral, a rod 238c connected to the said lever and a further lever 238d hinged to the structure 49b which engages with the said cam through a roller 238e.

Furthermore, the said inserter assembly 410 also has a tongue shaped member 239 carried by an arm 240 loosely mounted on the aforementioned shaft 238 and this stretches until its tip 241 engages with a spring 242 which keeps it pressed and up against the arm 237.

An adjusting screw 243 enables the tension to be regulated.

A shoulder 244 which is adjustable and is supported by the structure 49b has one of the ends of the spring

242 anchored to it and this serves as a limit for the angular clockwise rotation of the arm 240.

Still with the disc 178 immobile, the shaft 238 completes a clockwise rotation.

As a consequence of this, the tongue shaped member 239, under the tension of the spring 242 which causes the rotation of the arm 240, presses on the front part of the considered label 217, the rear of which is already in contact with the bag. In this way, the whole label is placed astride the top of the bag with the incorporated thread between the said top and the rear skirt of the label.

The arm 240 reaches its limit of movement.

The shaft 238 continues its angular rotation.

At this point the presser 236 starts functioning and reaches the top of the label 217 and pushes it onto the bag which it has already been skirting.

Upon completion of this particular operation, the considered bag finds itself in the condition shown on FIG. 35.

The considered gripper 19 closes and thus holds the label and obviously the bag and the support member 411 moves away.

When the above mentioned inserter assembly 410 has performed its task, it moves out of the zone as a result of the shaft 238 reversing.

The presser 236 first moves away from the considered label 217 and during the return travel, the arm 237 presses itself against the head of the screw 243.

In this way, the arm 240 overcomes the pull exerted by the spring 242 and places itself in its original condition.

While the aforementioned final operations are proceeding, the disc 178 is ready to receive a labelled thread in accordance with the operational details given in the foregoing and pertaining to the disc.

It is of the utmost importance for a thread to always be secured to the disc 178 from the infeed side, since there would be serious problems if the end of the thread had each time to be grasped.

When the label inserter assembly 410 has completed its operations on the bag and has been carried out of the zone, the conveying head 2 is able to start up again and to complete a further clockwise rotation of 30° to carry the considered bag to the station S8.

With reference to FIGS. 36, 37, 38, 39 and 40, a description will now be given of the mechanical group used to insert the metal staples with which the thread is fastened, as previously mentioned, to the considered label and to the relevant bag.

Although mention has in fact been made of two staplers, there really is only one stapler 233a (see FIG. 1) but this is provided with twin bodies 221 and 223 which operate alternatively over two diametrically opposed areas outside the aforementioned disc 178 or, to be more precise, in conjunction with the block 220 and the block 222a, respectively.

With particular reference to the FIGS. 36 and 37, the two bodies 221 and 223 are carried by a support frame 303 which is hinged to the structure of the machine where the shaft 304 is located, obviously so that it can be moved out of the previously considered operational zone.

A rotating sector 305 operated by a handle 306 fits into a stop 307 integral with the main structure of the machine, in order that the stapler can be locked in its working position.

FIG. 37 provides a cutaway drawing of one single body of the stapler, that is to say, the body 223 but it is understood that the body 221 has identical characteristics. The said body 223 is provided with a hollow shaft 301 which slides axially within a support 302 which is a part of the support frame 303.

Two axial stems 312 and 313, respectively, are contained inside the hollow shaft 301 and these terminate in a fork 314 and in an expulsion strip 315 (see FIG. 38).

In the front, on one side of the hollow shaft 301 (refer again to FIG. 38) a small lever 316 is secured and this has its front extremity folded over so that it can work in conjunction with the aforementioned fork 314 under the pressure of a spring 317.

The hollow shaft 301 and the coaxial stems 312 and 313 are restrained towards the inside of the support frame by a set of springs 318 (FIG. 37).

On the top of the hollow shaft (301) there are two cutting spigots 319 and 320 (see FIG. 38) and these lay across the external edges of the fork 314 for purposes which will be clarified in due course.

The axial forward movement of the described parts is derived from a rocker 321 (FIG. 37) which is hinged at point 322 to the support frame 303.

The rocker 321 is integral with a lever 321a connected by means of an arm 323 to an L-lever 324 hinged at point 325 to the support frame 303 which, through a roller 327 engages with a cam 326 rigidly mounted on a driven shaft 308.

The said driven shaft 308 derives its motion from a drive shaft 309 (FIGS. 36 and 37) carried by the structure of the machine.

The coupling of the shafts 308 and 309 is achieved through two flanges 300 and 311 which are integral with the shaft 308 and with the shaft 309, respectively, and are united from the front.

Two spools 331 and 331a (FIG. 36) feed continuous metal wires 331b and 331c to the groups 223 and 221.

The infeed of the said wires is achieved by means of a ratchet device 332, a knurled wheel 333 and a set of supports which are globally shown as 334.

A description will now be given, still with reference to the group 223 and FIGS. 38, 39 and 40, of how a metal staple is formed and expelled.

The wire 331c is taken opposite the fork 314 underneath the cutting spigots 219 and 220.

Given a push by the rocker 321 which is made to rotate clockwise, the arm 223 moves towards the block 222 and, initially, the fork 314 presses the wire up against the cutting spigots 219 and 220 thereby causing a section of the wire to be sheared and this section remains gripped by the said fork 314.

The fork 314 then moves, meets the folded extremity of the lever 316 which, in contrast with the fork itself, U-folds the previously sheared section (see FIG. 39).

With a third and final operation, due to the forward motion of the stem 313, the expulsion spring 315 pushes the formed staple outside the body 223 whilst the lever 316 meets with a spigot 329 on the support 302 and moves outwards, freeing the said staple which, in the case under consideration is used, with the assistance of the block 222a, to attach a thread to the considered bag.

Using an identical system, the arm 221 carries a staple to the block 220.

In relation to the aforementioned station S8 and FIGS. 41, 42 and 43, a description will now be given of a group 335, visible in FIG. 1, for sheathing or enveloping a considered bag.

The said group (see FIG. 41) is fundamentally composed of rod shaped means 336 and 337 which slide axially in the direction of the conveying head 2 and are operated by a mechanical assembly visible in FIGS. 42 and 43.

The sliding of the said rod shaped means 336 and 337 is controlled by two cams 336' and 337' rigidly mounted on a shaft 344 sustained by the support structure 344a carrying the complete assembly fixed to the structure 1 of the machine. The shaft 344 stretches to the rear of the machine and is connected to a pinion 345 in mesh engagement with the previously mentioned chain 194 (see FIGS. 2 and 43). The cams 336' and 337' are connected to the rod shaped means 336 and 337 by means of two levers 340 and 341, respectively, pivoted on to a shaft 400 supported by the structure 344a which engages with the said rod shaped means at point 342 and point 343.

The first rod shaped member 336 (see FIGS. 1, 41 and 42), has at the top a gripper 346 which is kept closed by flexible means incorporated in it but which are not shown in the drawing. The opening of the said gripper 346 is brought about by a rod 347 which presses on the jaws 346a and 346b of the gripper hinged to their support in the form of a lever.

When the rod shaped support in which it is contained extends forwards, the rod 347 is stressed from the rear, for reasons which will be seen in due course, by a tappet 348 belonging to a rocker 349 pivoted on to a shaft 349a supported by the structure 344a, operated by a rod 350 connected to a lever 350a, pivoted on to the shaft 400, the engagement with a cam 350b rigidly mounted on the aforementioned shaft 344 being established through a roller.

On the top of the rod shaped member 337 there are two overlapping suction units 351.

Another pair of suction units 352 is able to rotate around a spindle 353 and these are forced by rack devices 354 to undergo a forward rotation in the direction shown on FIG. 42 until they are in the direction of the shaft of the rod shaped members 336 and 337.

The rack devices 354 are moved by a cam 354a to which they are connected by means of a lever 354b mounted on the shaft 400 which engages with the said cam and at point 354c with the said rack devices (see FIG. 42 and FIG. 43).

The suction units 352 are designed to pick up a sheet of paper 355a on a plane 355, this sheet being derived from a web 361 taken from a reel 361a held by the structure of the machine and this is also visible in FIG. 1.

An articulated system 358 operated by a cam 359 (see FIG. 43) actions a knife 360 which cuts a sheet in the required size from the said web 361.

A description will now be given of the operation of the sheathing or enveloping group.

With the conveying head 2 at a standstill, the considered bag is located at the station S8.

The gripper 346, operated by the tappet 348, takes the considered bag and the grippers 19 corresponding to the arm 30' carrying the bag open.

The rod shaped member 336 retracts and the bag is fully extracted from the conveying head 2.

At this juncture, the suction units 352 rotate forwards and meet with the suction units 351.

At the very moment when the suction units 352 cease moving, a pressure inverter valve, not shown, places the suction units 352 in free air and puts under vacuum the suction units 351 which, see FIG. 2, are connected to a vacuum pump.

The suction units 352 return to their former position.

At this point the rod shaped member 337 moves forward. In this way, the sheet 355a is forced up against two walls 355b (see FIG. 41) and is virtually folded into a V, in which condition it is taken to the conveying head 2.

At the same time, the rod shaped member 336 moves forward and what then happens is that the considered bag is wedged between the folds of the sheet 355a and that the lot is passed to the gripper 19 of the considered arm 30' and the said gripper closes.

Moved by the tappet 348, the gripper 346 opens thus freeing the bag.

The rod shaped members 336 and 337 are returned to their original position and the conveying head 2 undergoes a further 30° clockwise rotation to carry the considered bag to the station S9.

At the said station S9 (see FIGS. 41 and 44), there is a device 364 which folds the previously partly pre-formed top flap on the envelope.

The said device operates in conjunction with a fixed spigot 401 and it is operated by a cam 402 (FIG. 42) rigidly mounted on the shaft 344 to which it is connected by means of a lever 403 hinged at point 403a to the structure 344a and by means of a tie rod 404.

Once the device 364 has ceased to operate, the conveying head 2 rotates a further 30° clockwise and carries the considered bag, duly sheathed, to the station S10.

At the aforementioned station there is a pick-up assembly 405 composed of a set of knurled wheels 365 and an oscillating gripper 366, also visible in FIG. 1, and this pick-up assembly takes the sheathed bag from the conveying head 2 and carries it to an exit 367 (see FIG. 1).

As the considered bag is leaving the conveying head 2 it passes through the knurled wheels 365 and thus the edges of the envelope are mechanically sealed and the pack is completed.

What I claim is:

1. An apparatus for forming and filling paper bags comprising: a rotatably mounted conveying head having a plurality of arms extending radially outwardly therefrom in circumferentially spaced-apart relationship; a plurality of work-gripping means mounted on respective ones of said arms for releasably gripping a paper object to be worked upon; means for intermittently rotating said conveying head to sequentially and intermittently advance said work-gripping means along a predetermined path of travel; bag-forming means positioned along said path of travel cooperative with said work-gripping means to form a paper bag from a strip of paper; bag-filling means operative when said work-gripping means is moved to a predetermined position along said path of travel to fill a paper bag gripped by said work-gripping means with a granular product; means operative when said work-gripping means is

moved to another predetermined position along said path of travel for applying a string and label composite to a filled bag gripped by said work-gripping means; and means for removing a filled bag from said work gripping means and applying a protective covering thereon and then returning the covered bag to the work gripping means.

2. An apparatus according to claim 1; wherein said bag-forming means comprises strip-cutting means for cutting a predetermined length of paper strip from a paper strip supply; a movably mounted sword movable to a first position to receive draped thereover said length of paper strip and movable to a second position; and means cooperative with said sword during movement thereof to said second position to effect folding of said length of paper strip into a paper bag.

3. An apparatus according to claim 2; wherein said last-mentioned means comprises a shaping funnel positioned to receive therein said sword during movement thereof to said second position; said shaping funnel having mounted therein first and second pairs of wedge-shaped elements cooperative, respectively, with first and second pairs of helically-shaped elements to effect folding of said length of paper strip during insertion of said sword into said shaping funnel.

4. An apparatus according to claim 2; wherein said strip-cutting means comprises a pair of rotatably mounted feed rollers positioned to receive therebetween a paper strip from said paper strip supply; means for rotationally driving said feed rollers to effect feeding of said paper strip to a cutting zone; rotatably mounted cutting assembly positioned in said cutting zone operative to cut said predetermined lengths of paper strip from the paper strip fed by said feed rollers; and means mounting said feed rollers and cutting assembly for movement together as an integral unit in

synchronization with the movement of said sword to effect draping of the cut length of paper strip over said sword when said sword is in said first position.

5. An apparatus according to claim 1; wherein said bag-filling means comprises means defining a storage chamber containing therein a supply of granular product; a rotationally driven product dispensing mechanism disposed within said storage chamber operative during rotation to supply a predetermined dosage of granular product into a paper bag gripped by said work-gripping means; and means for variably setting the dosage supplied by said product-dispensing mechanism.

6. An apparatus according to claim 1; wherein said string and label applying means comprises means for cutting a label from a supply reel of labels; a supply of string; means for attaching an end of said string to said label; means for cutting a predetermined length of the attached string from said supply of string; and means for attaching the string and label composite to a filled paper bag when same is positioned in said further predetermined position.

7. An apparatus according to claim 6; including means operative after said predetermined length of string is cut to effect folding of said label; and means for positioning the folded label over a portion of the filled paper bag with said predetermined length of string positioned between the folds of said folded label.

8. An apparatus according to claim 1; wherein said covering means includes a pair of rotatably mounted knurled wheels operative during rotation to mechanically close edge portions of said protective covering; and means for rotationally driving said knurled wheels.

* * * * *
